TYPOGRAPHICAL MACHINE

Walter H. Medford, Brooklyn, N. Y., assignor to
 News Syndicate Co. Inc., New York, N. Y., a corporation of New York

Application September 21, 1932, Serial No. 634,116

8 Claims. (Cl. 199—43)

My invention relates to improvements in a typographical machine.

One of the objects of my invention is to improve typographical machines which have a plurality of matrix magazines, for supplying different founts of type.

Another object of my invention is to improve a typographical machine having a plurality of magazines, in which the matrices of the different founts have corresponding combinations. This type of typographical machine is known in the trade as Mergenthaler Linotype No. 8 but it is to be understood that my improvements relate to all types of typographical machines, having a plurality of magazines.

Another object of my invention is to provide new and improved means which prevent the changing of the magazine unless the last line of matrices which has been set, has been fully distributed before the magazine is changed.

Another object of my invention is to generally improve the operation of a typographical machine which has a plurality of magazines, so as to prevent the matrices from entering the wrong magazine.

Another object of my invention is to prevent the changing of the magazines, while the matrices have not yet reached the distributor bar, so that the magazines cannot be changed while the matrices are retained on the second elevator bar, or in the distributor box.

Another object of my invention is to provide improved means for preventing the changing of the magazines, while the matrices are on the distributor bar.

Generally speaking the improvements make it impossible to change the magazine, until all the matrices have been caused to enter the magazine which is being shifted.

Other objects of my invention will be set forth in the following description and drawings which illustrate a preferred embodiment thereof, it being understood that the above general statement of the objects of my invention is intended merely to generally explain the same and not to limit it in any manner.

Fig. 1 is a front elevation.

Fig. 1a is a rear elevation.

Fig. 2 is a sectional view on the line 2—2 of Fig. 1.

Fig. 3 is a sectional view on the line 3—3 of Fig. 2.

Fig. 4 is a sectional view on the line 4—4 of Fig. 2.

Fig. 5 is a sectional view on the line 5—5 of Fig. 2.

Fig. 6 is a sectional view on the line 6—6 of Fig. 1.

In this view one of the control devices is in its operative position and the shifting of the mag-

azines is prevented because there are some matrices upon the distributor bar.

Fig. 7 is a sectional view on the line 7—7 of Fig. 6.

Fig. 8 is a view similar to Fig. 6, showing the position of the parts when the matrices have been cleared from the distributor bar, so that the magazines can be changed.

Fig. 9 is a sectional view on the line 9—9 of Fig. 8.

Fig. 10 is a view similar to Fig. 1, showing another embodiment of the invention.

Fig. 11 is a side elevation showing a detail of the control which is illustrated in Fig. 10.

Fig. 12 is a plan view, partially in horizontal section showing the modified screw guard which is shown in Figs. 10 and 11.

For many years it has been a frequent experience to have the operators of typographical machines of the multiple magazine type, change the magazines before all the matrices which belong to said magazine have entered the same. This has been a frequent source of serious errors in printing, and this has also caused the jamming of the machine, and the loss of a great deal of time.

According to my invention a plurality of controls is provided, which prevents the changing of the magazines, unless all the matrices are properly located in their respective magazines.

In order to clearly illustrate my improvements, I have illustrated a number of the essential parts of a well known typographical machine (Mergenthaler #8) but the improvements generally apply to any type of typographical machine.

In the type of machine illustrated herein, there are three magazines 1, which are mounted upon a common base 1a. Said base 1a is mounted upon a vertically movable member 1b, which is moved up and down by the operator, in the well known manner, in order to change the magazine.

Referring to Figs. 1, 1a and 6, the machine is provided with distributor screws or worms 3, and these are of the usual type. These distributor screws 3 operate to feed the matrices M along the distributor bar 4, in the usual manner. The distributor screws 3 are actuated in the usual manner by a conventional drive 2, which is operated by the usual belt 2a.

Referring to Fig. 2, the magazines are shifted up and down in the direction parallel to the arrow 18, in order to change a magazine. The frame of the machine, including the various frame arms is generally designated by the reference letter F.

Referring to Figs. 2, 7 and 8, the base 1a is provided with a suitable number of slide bars 19, which are of the well known type. As shown in Fig. 3, each said bar 19 is connected to the base 1a by means of suitable bolts, and each said bar 19 is provided with a pair of cutouts or recesses 20 and 20a.

- Magazine locating bars or bolt-bars 17 are provided in the usual manner and each of these bars 17 is provided at each end thereof with a head or enlargement 21. When said heads or enlargements 21 enter the top cutouts 20a, the bank of magazines is in its bottom position so that the top magazine 1 is in the operative position. When these heads or enlargements 21 enter the recesses 20, the intermediate magazine 1 is in the operative position. When these heads or enlargements 21 abut and engage the bottom surfaces of the bars 19, the bank of magazines is in its top position, and the bottom magazine 1 is operative.
- The magazine locating bars 17 are held in their operative positions, in which they prevent the changing of the magazines, by means of springs 22. Said springs 22 are suitably connected to the frame of the machine and to studs which project from said bars 17.
- Referring to Figs. 6 and 8, one of the magazine locating bars 17 is provided with a laterally projecting stud or pin 39. The guard-lever 36 for the distributor screws 3, is pivotally connected to the frame of the machine, by means of the pivot member 37. The movement of said lever 36 in the counter clockwise direction, is limited by the pin or banking screw 36a, which is suitably connected to the frame of the machine.
- Referring to Figs. 1, 6 and 7, the screw guard 31 is of the usual type, and this is connected in the usual manner to the bottom ends of arms 32, which are turnably mounted upon a rod 33. The rod 33 is connected to arms 34, which form part of the frame of the machine. Tension springs 35 operate to maintain the guard 31 against the upper end of lever 36.
- The bottom of the guard lever 36 is provided with a cam-shaped extension 38, which may be integral with said lever 36, or may be suitably connected thereto.
- As shown in Fig. 6, said extension 38 has a tapered face which positively engages the pin 39 of the locating bar 17.
- The lever 36 therefore positively locks the bar 17 in position, thus making it impossible to change the magazine, as long as there are any matrices M remaining upon the distributor bar 4.
- The face of the extension 38, which contacts with the pin 39, may have a very slight taper 50 and be almost perpendicular to the bars 17 so as to diminish the leverage of the pin 39 against the lever 36. This construction makes it impossible for the operator to force the bars 17 out of the position shown in Fig. 6, while there are matrices upon the bar 4. When the matrices have been cleared from the bar 4, the operator can turn the guard lever 36 to the inoperative position shown in Fig. 8, by shifting the bar or bars 17.
- It is to be understood that there are a number of the bars 19 and 17 in the device, but that it is only necessary to provide a single guard lever 36, which is associated with one of said bars 17.
- It has been proposed to utilize a distributor screw guard of the type of member 31. However in constructions of the present type the plate 31, which is flexible, can be bent or jammed against the matrices so that the magazine can be changed while there are matrices remaining 65 upon the bar 4. However the construction illustrated herein causes the screw guard 31 to have a large movement when the lever 36 is actuated, so that the end of said guard 31 is underneath the central plane of the distributor bar 4 when the bolt-bar 17 is in the inoperative

position shown in Fig. 8. It is therefore impossible for a careless operator to manipulate the bolt-bar 17 to such an extent as to spring the guard 31 and to remove the bolt-bar 17 to its inoperative position, if there are matrices on bar 4.

Referring to Figs. 1 and 1a, the device is provided with a second elevator bar 5 of the usual type, having the usual head 5a, which is brought into alignment with the distributor bar 4 when said bar 5 is raised to the position shown in Fig. 1. In order to shift the matrices M from the head 5a to the distributor bar 4, mechanism of the usual type is employed, as the invention consists of a special control which is later described. The mechanism for shifting the matrices from the head 5a to the bar 4 comprises a lever 6 which is connected to a link 7, which is pivotally connected at 8 to a block or slide 14.

Fig. 1 shows the dotted line position of the block 14 when the shifting mechanism is about to shift the matrices from the head 5a to the bar 4. In the full line position of the slide 14 which is illustrated in Fig. 1, the matrices have been completely shifted through the distributor box 11.

Referring to Figs. 1 and 2, the slide 14 is connected to a bar 9, which is connected to a head 10. The head 10 pushes against the matrices M in order to shift them on to the bar 4, and to force the matrices through distributor box 11.

Referring to Figs. 1a and 2, a separator bar 12 of the usual type is provided, and this is provided with the usual separator or spacer 12a, so that the matrices are separated as they are shifted out of the distributor box 11, so that the spaced matrices M are engaged and fed along the distributor bar 4 by the distributor screws 3. This spacing mechanism is of the usual type.

Referring to Figs. 2 and 3 a control lever 23 is provided with a bottom extension 23b and with a top extension 23a. The bottom extension 23b enters an opening in one of the bolt-bars 17, so that said bolt-bar 17 cannot be shifted out of its operative position, as long as said extension 23b is in the opening of said bolt-bar. The control lever 23 passes through and is adjustably held in a bearing member 24. Said bearing member 24 has a shank 25 which abuts a plate 26, which is suitably connected to the frame of the machine by means of fastening members 27. The shank 25 is turnably held upon the plate 26, by means of a pivot member 28. Stop pins 28a are provided for limiting the turning movement of the control bar 23. A spring 29 has one end thereof connected to the plate 26 and the other end of said spring 29 engages said lever 23 so that said lever 23 is normally held in the operative or full line position which is illustrated in Fig. 3.

When the slide 14 is moved to the full line position shown in Fig. 1, in which position all of the matrices have been moved onto the bar 4, the bar 9 engages the upper extension 23a (as shown in Fig. 1) so that the extension 23b releases the associated bolt-bar 17. Fig. 3 also shows how the bar 9 engages the extension 23a, which is L-shaped, so as to turn the control lever 23 to the inoperative position. However the lever 23 does not fully release the bolt-bar 17 as long as any of the matrices are still on the head 5a or in the distributor box 11.

The movement of the slide 14 is limited by a stop 30.

The second elevator bar 5 is provided with the

usual spring 15, which is connected to a yoke 16 of the head 5a, said head 5a being turnably mounted upon the bar 5, in the usual manner.

As shown in Fig. 4, the upper end of the bolt-bar 17 is provided with a bevelled surface 17a, in order to facilitate the clearing of the bolt-bar 17 by the extension 23b.

It will be noted that both sets of controls illustrated herein cooperate in order to prevent the changing of a magazine, unless and until said magazine has received all its matrices.

It has heretofore been proposed to have the pin 39 engage the bottom surface of control lever 36, and to have said bottom surface make a very small angle with the longitudinal axis of bolt member 17, and such a construction has been extensively used for many years. However, if a careless operator moved the bolt member 17 away from its operative position, the pin 39 would ride along and jam against the bottom surface of lever 36 without turning the same substantially especially if said lever 36 were loosely mounted upon its pivot. The bolt 17 could thus be withdrawn from its operative position even if matrices were mounted on the distributor bar. Likewise, such construction did not move the guard 31 in a lateral path of sufficient length towards the bar 4, so that the guard 31 could bend against the matrices, thus permitting the release of the bolt. According to my invention, the lower branch of lever 36 is made sufficiently long, so that the path of movement of said guard plate 31 is long enough to allow for any bending of said guard plate, thus preventing release of bolt 17 unless bar 4 is clear of matrices. Likewise the pin 39 abuts lever 36 above the bottom surface thereof, so that pin 39 cannot slip along or jam against lever 36. The parts are so dimensioned and shaped as to cause the guard 31 to substantially assume the position shown in Fig. 8, before pin 39 contacts with the under-surface of lever 36.

Of course, the same result could be secured if the pin 39 contacted with a bottom surface of lever 36 which was sharply inclined with respect to the longitudinal axis of bolt 17. The pin 39 preferably remains in contact with the bottom part of lever 36, when the bolt 17 has been fully withdrawn to its inoperative position.

In the embodiments shown in Figs. 10-12, the member 23 and its appurtenant parts are eliminated, and a lock is provided for the screw guard plate 31, which prevents its release from the position shown in Fig. 6, unless all the matrices have been pushed through the distributor box 11, so that they are engaged by the screws 3.

As shown in Fig. 11, a plate 60 is rigidly connected at 61 to the frame of the machine. A pawl or locking member 62 is pivotally connected to the plate 60, by means of the pivot member 63. A blade spring 64 is connected to the plate 60 by means of the member 64a and this spring 64 bears against a pin 67 which projects from the locking member 62, so that said locking member 62 is turned in the counter clockwise direction, until said member 62 abuts a stop pin 65, which projects from the plate 60. For this purpose a suitable recess is formed in the edge of the pawl 62.

In the position shown in Figs. 11 and 12, the locking member 62 engages a recess 66 which is provided in the guard plate 31, so that said guard plate 31 is held in the position shown in Fig. 6, thus preventing any changing of the magazines.

As shown in Fig. 12, the recess 66 is of substantially triangular shape.

As the slide 14 reaches the end of its movement, it contacts with the upper end of the pawl member 62, turning the same in the clockwise direction, so that the member 31 is released, thus permitting the changing of the magazines. However the magazines cannot be changed until all the matrices have been pushed through the distributor box 11.

Of course the guard plate 31 cannot be moved away from the position shown in Fig. 6, until the matrices, all of which have been delivered to the distributor bar 4 so that they are engaged by the screws 3, have been caused to enter the proper magazine.

I claim:

1. In a typographical machine having a plurality of movable magazines and a distributor bar and shift mechanism for shifting the matrices on to said distributor bar and operating mechanism for moving said magazines, locking mechanism movable independently of said operating mechanism and adapted to hold said magazines in a predetermined position, said locking mechanism being non-releasable until said shift mechanism has operated to shift said matrices on to said distributor bar.

2. In a typographical machine having a plurality of movable magazines and a distributor bar and shift mechanism for shifting the matrices on to said distributor bar and operating mechanism for moving said magazines, locking mechanism movable independently of said operating mechanism and controlled by said shift mechanism, said locking mechanism being adapted to hold said magazines in a predetermined position until said locking mechanism is released.

3. In a typographical machine having a plurality of movable magazines and a distributor bar and shift mechanism for shifting the matrices on to said distributor bar and operating mechanism for moving said magazines, a movable bolt independent of said operating mechanism and adapted to hold said magazines in predetermined position, a lever adapted to engage said bolt in order to prevent the movement thereof, said shift mechanism having a member which is adapted to abut and to actuate said lever to its inoperative position, at the completion of the operating movement of said shift mechanism.

4. In a typographical machine having a plurality of movable magazines and a distributor bar and shift mechanism for shifting the matrices on to said distributor bar and operating mechanism for moving said magazines, a movable bolt movable independently of said operating mechanism and adapted to hold said magazines in predetermined position, said bolt having an opening adjacent an end thereof, a lever having lateral extensions at its upper and lower ends, said upper extension being L-shaped, said lower extension being adapted to enter said opening and to prevent the movement of said bolt away from its operative holding position, a spring adapted to urge said lever to its operative position, said shift mechanism having a member adapted to abut said upper extension in order to move said lever away from its operative position, at the completion of the operating movement of said shift mechanism.

5. In a typographical machine having a plurality of movable magazines and a distributor

- bar and operating mechanism for moving said magazines, a movable bolt independent of said operating mechanism and adapted to hold said magazines in predetermined position, a guard associated with said bar, said guard being laterally movable relative to said bar and having an edge thereof adapted to abut a matrix which may be mounted on said bar, a guard lever having one end thereof adapted to abut said guard, a pin on said bolt adapted to abut the other end of said lever above the bottom surface thereof when said bolt is in its operative position, said lever being adapted to actuate said guard towards said bar when said lever is actuated by the movement of said bolt to its inoperative position and when said bar is free from matrices, the path of said movement of said guard being sufficiently long to prevent said lever from releasing said bolt when there are matrices on said bar.
6. In a typographical machine having a plurality of movable magazines and a distributor bar and operating mechanism for moving said magazines, a movable bolt independent of said operating mechanism and adapted to hold said magazines in predetermined position, a flexible guard associated with said distributor bar, said guard being laterally movable relative to said distributor bar and having an edge thereof adapted to abut a matrix which may be mounted on said distributor bar, and actuating means actuated by the movement of said bolt towards its inoperative position, said actuating means being adapted to move said guard towards said bar in a path of sufficient length to cause said guard to flex and to compensate for any flexing of said guard, so that said guard when a matrix is on the bar prevents said movement of the bolt if there are matrices on the bar, the operating edge of said guard at least being substantially under the axis of said bar, when said guard is at the end of said path of movement.
7. In a typographical machine having a plurality of movable magazines and a distributor bar, a movable bolt adapted to hold said magazines in predetermined position, a flexible guard associated with said distributor bar, said guard being laterally movable relative to said distributor bar and having an edge thereof adapted to abut a matrix which may be mounted on said distributor bar, and actuating means actuated by the movement of said bolt towards its inoperative position, said actuating means being adapted to move said guard towards said bar in a path of sufficient length to cause said guard to flex and to compensate for any flexing of said guard, so that said guard when a matrix is on the bar prevents said movement of the bolt if there are matrices on the bar, the operating edge of said guard at least being substantially under the axis of said bar, when said guard is at the end of said path of movement.
8. In a typographical machine having a plurality of movable magazines and a distributor bar, and shift mechanism for shifting the matrices on to said distributor bar, a movable bolt adapted to hold said magazines in predetermined position, a guard associated with said distributor bar, said guard being laterally movable relative to said distributor bar and having an edge thereof adapted to abut a matrix which may be mounted on said distributor bar, holding means intermediate said guard and said bolt whereby said bolt is held in locking position when said guard is in a predetermined normal position, a locking member adapted to hold said guard in said predetermined position, and means actuated by said shifting mechanism for releasing said locking member from said guard.
